UNITED STATES PATENT OFFICE.

RUFUS A. FREEMAN, OF FLUSHING, NEW YORK.

MACHINE FOR MAKING SHEET-RUBBER ARTICLES.

1,340,884.

Specification of Letters Patent.

Patented May 25, 1920.

Application filed May 17, 1917, Serial No. 169,336. Renewed April 6, 1920. Serial No. 371,724.

To all whom it may concern:

Be it known that I, RUFUS A. FREEMAN, a citizen of the United States, residing at Flushing, in the county of Queens and State of New York, have invented certain new and useful Improvements in Machines for Making Sheet-Rubber Articles, of which the following is a specification, reference being had therein to the accompanying drawing.

10 This invention relates to the production of such articles as dress shields and the like from sheet rubber, and the invention consists of a machine of improved form and construction adapted to act on separate 15 sheets of rubber and to form therefrom the two flaps of a dress shield united along one edge.

The operation of my improved mechanism is based on the peculiarity of unvulcanized 20 sheet rubber that if two sheets be placed together or superposed one upon the other and subjected to the pressure of a comparatively dull or blunt edge or die, the sheets will be severed along said edge and the severed portions will at the same time become united 25 along their edges in the form of a joint resembling in certain respects a welded joint. But if the superposed sheets be subjected to the pressure of a sharp cutting edge, they 30 will be incised along said edge without the material becoming united.

To take advantage of this peculiarity in the production of dress shields consisting of two flaps or blanks united along their upper 35 edges, my improved mechanism embodies two sharp cutting edges or incising dies carried respectively by rotary rolls and adapted to act on separate sheets of rubber and to make incisions therein, thus forming the 40 two flaps of the shield, rotary means for superposing said sheets one upon the other and causing the incisions to register with each other, and a comparatively dull cutting edge or severing die carried by a rotary roll 45 and adapted to act on the superposed sheets and sever the same along a line connecting the ends of the incisions and corresponding to the upper edge of the dress shield, while at the same time causing the material of the 50 incised portions or flaps to unite with each other along said edge.

The material is wound in the form of supply rolls on two spools rotatably supported in the machine so that the sheets may be wound therefrom and supplied to the machine, the two sheets being fed continuously

through the machine and being acted on by the incising and severing dies in succession, with the result that finished dress shields, consisting of the two flaps connected together along their upper edges, will be produced continuously in succession from the two sheets.

In the accompanying drawings:

Figure 1 is a longitudinal sectional elevation of a machine constructed in accordance with my invention.

Fig. 2 is a top plan view of the same.

Fig. 3 is a sectional view on an enlarged scale of one of the incising dies and its carrying roll.

Fig. 4 is a similar view of the severing die and its carrying roll.

Fig. 5 is a development of the surface of one of the die rolls showing the form and 75 contour of the incising dies.

Fig. 6 is a similar view of the roll carrying the severing dies showing the form and contour of said dies.

Fig. 7 is a diagrammatic perspective view 80 showing how the two sheets are incised separately and then superposed and the incised portions severed and united.

Referring to the drawings:

The operative parts of the machine are 85 mounted in a suitable frame 1 supported by legs 1^a. Extending upwardly from said frame at opposite sides are two standards 2, 2, provided each with two bearings 3, 3, in which are mounted journals 4, 4, on the 90 ends of two horizontal rotary rolls 5 and 6 which are arranged side by side parallel to each other. The roll 5 is provided at diametrically opposite sides with incising dies 7, each in the form of a sharp cutting edge or 95 knife, as shown in Fig. 3, of a contour corresponding to the flap of a dress shield as shown in Fig. 5. The roll 6 is likewise provided on opposite sides with similar incising dies 8, which dies on the two rolls are 100 adapted to act on separate sheets 9 and 10 respectively of unvulcanized rubber, which sheets are fed to the action of the dies in the manner to be more fully described hereinafter, with the result that incisions 11 and 105 12 will be formed in the sheets as shown in Fig. 7.

Mounted in bearings in the frame beneath the two rolls 5 and 6 are two horizontal cylindrical platen rolls 13 and 14, 110 the surfaces of which are in such proximity to the die rolls that the material passing

between the die rolls and platen rolls will be supported by the latter and presented to the action of the dies, the surface of the platen rolls being preferably of smooth steel.

- 5 Beneath the two platen rolls is a third horizontal die roll 15 mounted at its ends in bearings 16 on the frame. This die roll carries at diametrically opposite sides two comparatively dull cutting edges or 10 severing dies 15^a of the form shown in Fig. 4, and curved to correspond to the upper edges of the flaps of the dress shield. The severing dies are adapted to act on the two incised sheets after they have been 15 brought together and superposed one upon the other with the incisions in registry with each other, and in the action of the severing die on the sheets thus superposed, the incised portions of the sheets will be severed 20 from the main body of the sheets along a curved line 17 (see Fig. 7), which line will connect at its ends with the incisions 11 and 12 and form the upper edge of the dress shield.
- 25 The severing die is of the peculiar form shown in Fig. 4 in order that in addition to its severing action on the material, the latter will be caused to unite, with the result that the incised portions 11^a and 12^a 30 of the sheets will be joined together along their upper edges. To bring about this uniting action of the material, the extreme edge of the die is dull or flat as at 16^a, one side of the die is straight as at 16^b, 35 and the other side is beveled or inclined outwardly away from the straight side as at 16^c. In the action of the die on the superposed unvulcanized rubber sheets the flat edge 16^a, and the beveled side 16^c will 40 coöperate with each other in compressing the material of the incised portions as these portions are severed from the body of the sheets by the straight side 16^b of the die, the result being that while the incised portions 45 will be completely separated and severed from the main bodies of the sheets, the two portions will be united with each other and joined together at their upper edges in an integral welded joint.
- 50 As shown in Fig. 1, the two sheets of material 9 and 10 are led from two supply rolls 9^a and 10^a wound on horizontal spools 18 and 19 rotatably mounted in bearings 55 in standards 20 and 21 extending upwardly from the machine frame at its opposite ends. From these rolls the two sheets pass respectively around horizontal guide bars 22 and 23 arranged at the outer ends of two tables 24 and 25 which are fixedly supported in an inclined position and slope 60 downwardly toward each other and have their inner lower ends terminating in proximity respectively to the die rolls 5 and 14 and the underlying platen rolls 13 and 14 65 so as to direct the material into the bites

of said rolls. After passing between the die rolls and platen rolls the two sheets are drawn together between the platen rolls and superposed one upon the other, and after leaving these rolls, the sheets in superposed condition are directed by guide plate 70 25 between the right hand platen roll 13 and the underlying die roll 15 carrying the severing die.

These several rolls being driven in the 75 direction of the arrows in Fig. 1 by the driving mechanism to be more fully described hereinafter, the two sheets from the separate supply rolls will be drawn into the machine from opposite sides and passing between the die rolls and the underlying platen rolls, the sheets will be incised separately as before described, and as they enter between the two platen rolls they will be brought together and the incisions 80 85 therein caused to register with each other. In this condition they pass between the platen roll 13 and the underlying die roll 15, and the severing die acting on the two sheets, the incised portions will be severed 90 therefrom along the line 17 (see Fig. 7) and at the same time the severing die will cause the said portions to become united, thereby producing a finished dress shield.

The power to drive the several rolls is 95 imparted by means of a pulley 26 which is clutched to the journal of the platen roll 13. The roll 13 is provided with a spur pinion 27 which engages a spur pinion 28 on the overlying die roll 5. The 100 pinion 28 on the die roll 5 engages a pinion 29 on the companion die roll 6 so that by the train of gearing described, the two upper die rolls are rotated in opposite directions. The platen roll 14 receives rotary motion from its companion roll 13 by means of a spur pinion 30 on the roll 14 which is driven by the pinion 27 on the roll 13; and the lower die roll 15 receives its motion from the platen roll 13 by means 105 of a pinion 31 on the roll 15 which is engaged and driven by the pinion 27 on the roll 13. As a result of the train of gearing described, all of the rolls are positively driven in the direction indicated by 110 the arrows in Fig. 1, the two upper die rolls rotating in opposite directions so as to draw the two sheets inwardly toward each other from the supply rolls, the two platen rolls rotating also in opposite 115 directions to each other and oppositely to the two die rolls in order to coöperate with said rolls and in order to draw the two sheets together between them, and the lower die roll rotating in a direction opposite to the platen roll with which it co- 120 operates, so as to continue the feed of the two sheets and bring about the action of the severing dies thereon.

It is important that in the feed of the 130

material through the machine it be free from strain or tension, since by reason of the peculiar condition of the rubber in its unvulcanized state, any pull or strain thereon will permanently deform or distort the same. I therefore provide for feeding the material without imposing any pull or strain thereon, and this I accomplish by positively rotating the two supply rolls 9^a and 10^a so as to unwind the material therefrom, and the rotation of the several dies and platen rolls is so timed that their surface speed will be the same as that of the delivery of the sheets from the supply rolls, the two sheets hanging loose where they leave the supply rolls as at A, thereby producing a slack at this point.

To accomplish this method of feed of the material, the supply rolls are acted on by mechanism which operates to positively rotate the rolls and unwind the material therefrom, and as these mechanisms are the same for both rolls, a description of one will suffice. A small roller 32 is mounted fixedly 25 on a horizontal shaft 33 and engages the surface of the roll of material, so that when the shaft is rotated in the direction of the arrow, the roll of material will be rotated so as to unwind the sheet therefrom. The 30 shaft 33 is journaled in the upper ends of two parallel upright arms 34 the lower ends of which are fixed to a horizontal rock shaft 35 mounted in suitable bearings on the machine frame. The two arms 34 and the 35 shaft 33 thus form in effect a frame carrying the roller 32 which frame is rockable about the axis of the rock shaft so that the roller can be maintained in constant engagement with the roll of material notwithstanding the decreasing diameter of the roll as the sheet is unwound therefrom. This frame is acted on by a counter-weight 36 carried by a bar 37 fixed to and projecting horizontally inwardly from the rock shaft 35, 40 the tendency of the weight being to swing the upper end of the frame inwardly and thereby hold the roller yieldingly pressed against the roll of material.

The shaft 33 has fixed to it a pulley 38 50 driven by a belt 39 from a driving pulley 40 mounted loosely on the rock shaft 35. The hub on the pulley 40 has fixed to it a second pulley 41, and driving belts 42 are passed over the pulleys 41 at the two ends 55 of the machine and extend inwardly toward each other and pass around pulleys 43 and 44 respectively on the two platen rolls 13 and 14. As a result of this construction and arrangement of the parts, the motion of the 60 two platen rolls will be imparted to the two rollers 32 which will be rotated in engagement with the supply rolls 9^a and 10^a and will turn the rollers in a direction to unwind the sheets therefrom.

65 It is seen therefore that while the two

sheets are drawn positively through the machine by the rotation of the several rolls, they are not subjected to any pull or strain which would be liable to injure the material, since the supply rolls are positively rotated so as to unwind the sheets therefrom at the same rate of speed at which the sheets are drawn through the machine; the possibility of any tension on the material being avoided by the slack portions of the sheets where they hang loose in passing between the supply rolls and inclined tables.

Having thus described my invention, what I claim is:

1. In a machine of the type described, 80 the combination of two rotary die rolls provided with incising dies adapted to act on separate sheets of material and form incisions therein, rotary means adapted to draw the incised sheets together and super- 85 pose one upon the other with the incisions in registry with each other, and a rotary die roll provided with a severing die, adapted to sever the incised portions from the sheets and formed to unite the two in- 90 cised portions.

2. In a machine of the type described, 95 the combination of two die rolls provided with incising dies, platen rolls coöperating with said die rolls, means for feed- 100 ing separate sheets of material between the platen rolls and die rolls, whereby incisions will be formed in the sheets, said platen rolls being adapted to draw the incised sheets together and superpose one upon the other with the incisions in registry with each other, and a die roll provided with a severing die adapted to act on the super- 105 posed sheets and to sever the incised portions therefrom, said severing die being formed to unite the incised portions of the sheets.

3. In a machine of the type described, 110 the combination of two rotary die rolls provided with incising dies, platen rolls with which said dies coöperate in incising sepa- 115 rate sheets passing between said rolls, the said platen rolls being adapted to draw the incised sheets together between them and superpose them one upon the other with the incisions in registry with each other, and a die roll formed with a severing die coöperating with one of the platen rolls in severing the incised portions of the two sheets, said severing die being formed to unite the incised portions of the sheets.

4. In a machine of the type described, 120 the combination of a frame adapted to support a supply roll of the material to be acted on, a rotary die roll mounted in the frame and adapted to act on the material from the supply roll and to feed the same continuously through the machine, and means independent of the die roll adapted to unwind the supply roll continuously, said unwinding means being so coördinated in its action 125 130

and so timed with relation to the rotation of the die roll as to unwind the material at the same rate of speed that it is fed by the die roll.

5. In a machine of the type described, the combination of a frame adapted to support a supply roll of the material to be acted on, a rotary die roll mounted in the frame and adapted to act on the material from 10 the supply roll and feed the same continuously through the machine, the said material arranged to hang slack and free of tension between the supply roll and die roll, and means independent of the die roll adapted 15 to unwind the supply roll continuously to supply the slack material, said unwinding means being so coördinated in its action and so timed with relation to the rotation of the die roll as to supply the slack material at 20 the same rate of speed that it is fed by the die roll.

6. In a machine of the type described, the combination of a frame adapted to give support to two supply rolls of the material 25 to be acted on, rotary die rolls provided with incising dies and severing dies adapted to act on the separate sheets of said material and incise the same and sever the incised portions therefrom, rotary means independent of the die rolls adapted to act on said 30 supply rolls and continuously unwind the material therefrom, and means for operating the die rolls to feed the material continuously through the machine, the said die 35 rolls and said rotary means being so timed and coördinated in their movements that the material will be delivered from the supply rolls at the same rate of speed at which it is fed through the machine.

40. 7. In a machine of the type described, the combination of a frame adapted to give support to two supply rolls of the material to be acted on, rotary die rolls mounted in the frame and provided with incising dies and 45 severing dies adapted to act on the separate sheets of material and incise and sever the same and feed the material continuously through the machine, the said material adapted to hang in two slack portions between the respective supply rolls and die 50 rolls, and means independent of the die rolls adapted to unwind each supply roll continuously to supply the slack portions of the material, said unwinding means being so coördinated in its action and so timed with 55 relation to the rotation of the die rolls as to supply the two slack portions of the material at the same rate of speed that the two sheets are fed by the die rolls.

60. 8. In a machine of the type described, the

combination of a frame adapted to give support to supply rolls of the material to be acted on, die rolls operable to feed sheets of material through the machine and incise the same, swinging frames provided with rollers engaging the material on the supply rolls to unwind the same, means acting on said frames to hold the rollers in yielding engagement with the supply rolls, means for rotating the die rolls to feed the material 65 continuously through the machine, and means for rotating the rollers to continuously unwind the material from the supply rolls, the rotation of the die rolls and rollers being so timed that the material will be delivered from the supply rolls at the same 70 rate of speed at which it is fed through the machine.

9. In a machine of the type described, the combination of a machine frame adapted to give support to supply rolls of the material to be acted on, rotary die rolls mounted therein and operable to feed sheets of material through the machine and incise the same, rock shafts mounted in the frame, 80 arms on said shafts, rotary shafts mounted in said arms, rollers on the rotary shafts in position to engage respectively the supply rolls and unwind the material therefrom, driving pulleys mounted loosely on 85 the rock shafts, pulleys fixed to the rotary shafts, driving belts passing over said pulleys, means for rotating the die rolls to feed the material through the machine, and driving connections between the die rolls 90 and driving pulleys for rotating the rollers to unwind the material from the supply 95 rolls.

10. In a machine of the type described, the combination of a frame adapted to give 100 support to a supply roll of the material to be acted on, a rotary die roll mounted therein, a rotary platen roll also mounted in the frame, said rolls being operable to draw the material to be acted on between them, a 105 supporting table sustained by the frame in position to direct the material between the die and platen rolls, means for rotating the supply roll to unwind the material therefrom, a guide bar at the outer end of the table over which the material is adapted to pass to the table and between which and the supply roll the material is adapted to hang loose, and means for rotating the die roll and platen roll to feed the material between them at the same rate of speed at which it is delivered from the supply roll.

In testimony whereof I have affixed my signature.

RUFUS A. FREEMAN.
